CLAIM

The ornamental design for a combined cover and base for a jar, as shown and described.

DESCRIPTION

FIG. 1 is a perspective view of a combined cover and base for a jar, embodying our new design;

FIG. 2 is a top view thereof;

FIG. 3 is a front elevation thereof, the rear and side elevations are the same;

FIG. 4 is a bottom view thereof; and,

FIG. 5 is a front elevation of an alternate embodiment of the combined cover and base for a jar that differs from the first embodiment only in the changes in proportions that are shown in FIG. 5.

The broken lines in the drawings are for illustrative purposes only and do not form part of the claimed design.
